(57) **CLAIM**

I claim the ornamental design for an infant bolster and swaddle wrap, as shown and described.

DESCRIPTION

FIG. 1 is a perspective view of an ornamental design for an infant bolster and swaddle wrap in accordance with the present disclosure;

FIG. 2 is a front elevational view of the infant bolster and swaddle wrap shown in FIG. 1;

FIG. 3 is a rear elevational view of the infant bolster and swaddle wrap shown in FIG. 1;

FIG. 4 is a right side elevational view of the infant bolster and swaddle wrap shown in FIG. 1;

FIG. 5 is a left side elevational view of the infant bolster and swaddle wrap shown in FIG. 1;

FIG. 6 is a top plan view of the infant bolster and swaddle wrap shown in FIG. 1;

FIG. 7 is a bottom plan view of the infant bolster and swaddle wrap shown in FIG. 1;

FIG. 8 is a perspective view of the infant bolster and swaddle wrap shown in FIG. 1 showing an infant partially covered by a portion of the infant bolster and swaddle wrap; and,

FIG. 9 is a perspective view of the infant bolster and swaddle wrap shown in FIG. 1 showing the infant fully wrapped.

The broken lines shown on FIGS. 1-9 show unclaimed detail only and form no part of the claimed design.
